UNITED STATES PATENT OFFICE.

WILLIAM D. BELL, OF COLUMBUS, OHIO.

FUEL-HEATING ATTACHMENT.

1,366,157.

Specification of Letters Patent. Patented Jan. 18, 1921.

Application filed August 7, 1919. Serial No. 315,804.

To all whom it may concern:

Be it known that I, WILLIAM D. BELL, a citizen of the United States, residing at Columbus, in the county of Franklin and State 5 of Ohio, have invented certain new and useful Improvements in Fuel-Heating Attachments, of which the following is a specification.

This invention relates to fuel heating attachments for internal combustion engines, and has for its general object to provide a simple, efficient and readily attachable device capable, when applied, of receiving the heat of the exhaust structure of an engine 10 and directing the heat thus received into intimate relation with the fuel charge passing through the intake structure of said engine, whereby a complete vaporization of the charge will be produced before combustion 15 and greater efficiency in engine operation obtained.

Another object of the invention resides in the provision of a plate member designed for application between the side of an engine 20 and the intake and exhaust manifolds thereof, said member having appropriately situated ports formed therein through which the products of combustion are circulated when passing into and from the manifolds, the construction and location of the plate member being such as to enable the same to be directly heated by the exhaust gases and also through the heat of the engine proper in order that said member 25 will attain a working temperature best calculated to produce effective results, said member further being formed from a heat conducting alloy whereby the wall of the port formed therein, through which the fuel 30 charge is passed after leaving the intake manifold, will be heated to such extent as to effect a complete vaporization of the fuel charge and such condensed fuel which may 35 form a part thereof, so that a highly combustible mixture will be produced and one wherein waste in fuel consumption is eliminated.

For a further understanding of the invention reference is to be had to the following description and to the accompanying drawing wherein:

Figure 1 is a side elevation of an internal combustion engine and illustrating the application of the fuel heating attachments 55 comprising the present invention thereto,

Fig. 2 is a detached perspective view of one of the heating plates,

Fig. 3 is a horizontal sectional view, and

Fig. 4 is a transverse vertical sectional view.

Referring more particularly to the details of the invention, use is made of an internal combustion engine 1, wherein is embodied the usual intake manifold 2 and the superimposed exhaust manifold 3. The rest of the engine may be of any desired construction, as the same has no particular bearing upon the present invention, the latter dealing specifically with an explosive engine broadly and its associated manifolds. In view of the present commercially used grade of gasoline, motor vehicle engineers have found it necessary to apply heat to the intake manifold for the purpose of preheating a fuel charge so as to insure a complete vaporization of the latter. Many prior devices along this line have simply resorted to the expedient of providing a heating chamber around the intake manifold, which had the effect of promoting vaporization. However, it has been my experience that the majority of these devices fail to produce the state of vaporization best adapted for engine efficiency. It is the purpose of my structure to provide means whereby heat from the products of combustion of an engine is transmitted to a port or duct through which the fuel charge is passed before the same enters the combustion chambers of the engine. By thus heating the wall or walls of said port any condensed fuel which may exist in the charge will be brought into contact with the heated walls of the port so that relatively complete vaporization of such nonvolatilized fuel will be afforded.

To this end, the present invention provides a plurality of plate members 4 of identical construction which, when in operation, are designed to be placed between the engine extremities of the exhaust and intake manifold and the side of the engine itself. These plate members are preferably formed from a heat conducting material such as aluminum or an alloy thereof, and in this instance said members are provided with ports 5 at the ends thereof. The outer ends of the latter are preferably countersunk as at 6 and thus provide sockets for the reception of the engine branches of the exhaust manifold 3. Through the provision

of the countersunk portion 6, said branches will terminate within the ports 5 in such manner that the walls of said branches will be in alinement with the inner walls of the 5 ports so that an unrestricted circulation of the exhaust gases from the engine, through the ports 5 and the branches of the exhaust manifold 3 will be provided. It will thus be manifest that the inner walls of the ports 10 5 are directly exposed to the heat of the exhausted gases, so that the bodies of the plate members are thus capable of being heated to a required degree. The heating of the plate members is also facilitated by placing the 15 same in direct contact with the cylinder head 7 of the engine, and owing to the material employed in the members, the heat conducted by the latter will be considerably high.

20 In order to take advantage of this heat, and to produce a more economically running engine, said members are provided centrally with intake ports 8. These ports are situated intermediately of the exhaust ports 25 5 and also have their outer ends countersunk as at 9 to receive the engine extremities of the intake manifold 2. The members 4 are also provided with bosses 10, which are located axially with respect to the ports 8 and 30 protrude from the inner face of the plate members in such manner as to elongate the length of the inner portions 11 of the ports 8, so that heating surfaces of extended length will be provided by the walls of said 35 inlet ports 8. By virtue of this construction it will be observed that the heat of the exhausting gases is directly received by the plate members 4 and this heat is then transmitted to the walls of the ports 8. Thus, before a fuel charge is introduced into the cylinders of the engine, said charge will be brought into direct contact with the walls of the ports 8 so that any condensation which 40 may exist in the fuel charge will be readily 45 vaporized by contact with the heated walls of the plate members. Also, the fuel charge as a whole is more completely vaporized, owing to the fact that its temperature is raised, and suspended particles of uncarbureted fuel entrained in the fuel mixture are also vaporized. Thus mechanism has been provided for effecting a relatively complete vaporization of the fuel before its introduction into the engine cylinders, so that economy 50 will obtain from a standpoint of fuel consumption and the general efficiency of the engine raised. Obviously, through the instrumentality of the plate members the gas conduits of the engine are so linked that a 55 rapid and effective interchange of heat exists.

60 To secure the plate members in position, the same are provided with elongated slots 12 through which are passed the bolt shanks 65 of the connecting brackets 13, the latter be-

ng of the ordinary type and are so arranged 70 to bridge adjacent branches of the engine extremities of the intake and exhaust manifolds, in other words the brackets or clamps 13 serve in their ordinary capacity of retaining the manifolds in position and in addition serve to securely retain the plate members 4 in their operative positions. The slots 12 are provided to accommodate the plate members to unevenly position pairs of 75 securing clamps. The inner ends of the exhaust ports 5 may be also provided with bosses 14 which correspond to the bosses 10 but ordinarily are not of the same length as the latter, however, all of said bosses are arranged to enter within receiving openings formed in the cylinder head 7, and said bosses are provided with surrounding gaskets 15, by means of which leakage in gas circulation will be eliminated when the 80 clamps 13 are properly applied.

In view of the foregoing description, taken in connection with the accompanying drawing, it will be apparent that there is provided an attachment of considerable utility 90 in the capacity named, and one which will be convenient to apply, effective in use and of an automatic nature, since the same does not involve any manual attention in operation. Owing to the extended length of the 95 inner portions 11 of the ports 8, substantially all condensation in the fuel charge will be eliminated and a thorough vaporization of the fuel charge as a whole will be obtained. The invention, therefore, provides 100 a structure in the nature of the plates 4 which will operate by giving up the heat supplied to them, to vaporize the fuel passing therethrough and in finally delivering this highly combustible mixture directly to 105 the cylinders, without the possibility of overheating the charge.

What I claim is:

1. In an internal combustion engine the combination with the intake and exhaust manifolds thereof, of a plate member formed from a heat conducting material interposed between said manifolds and the side of said engine, and said plate member having a plurality of ports formed therein situated to establish communication between the interior of said engine and said manifolds, certain of the ports of said member having their walls directly exposed to the heat of the exhaust gases passing from said engine to said exhaust manifold to receive the heat of said gases.

2. In an internal combustion engine, the combination with the intake and exhaust manifolds thereof, of a fuel heating member formed from a heat conducting material interposed between said manifolds and the side of said engine, said member being formed with a plurality of ports situated to register with the fluid passageways formed 130

65 of the connecting brackets 13, the latter be-

in said manifolds and engine, and means for retaining said member in its applied position in connection with said engine and manifolds.

5. 3. In an internal combustion engine, the combination with the intake and exhaust manifolds thereof, said manifolds having their engine branches terminated in substantially horizontal alinement, of a fuel heating member formed from a heat conducting material interposed between said manifolds and the side of said engine, said member being formed with a plurality of ports situated to register with the fluid passageways formed in said manifolds and engine, and means for retaining said member in its applied position.

4. In an internal combustion engine, the combination with the intake and exhaust manifolds thereof, of a plate member formed from a heat conducting material interposed between said manifolds and the side of said engine, said members being formed with a plurality of ports situated to register with the fluid passageways formed in said manifolds and engine, and securing clamps common to both the manifolds and said member.

5. A fuel vaporizing attachment for inter-

nal combustion engines comprising a plate formed from a heat conducting material, 30 means for fastening said plate between the manifolds and side of an internal combustion engine, said plate having a plurality of ports formed therein adjacent to its extremities for registration with the passages of the 35 exhaust manifold, and said plate being further formed with an intermediate port arranged for registration with the outlet passages of the intake manifold.

6. A fuel vaporizing attachment for internal combustion engines comprising a plate formed from a heat conducting material, said plate having ports formed therein adjacent to its extremities and said ports being designed for coöperation with the exhaust 45 manifold of an engine, said plate being further formed with a port disposed immediately of said former ports and said intermediate port being situated for connection with the intake manifold of said engine, and 50 said intermediate port being of greater thickness than the corresponding thickness of said plate by providing an axial extension upon the rear face of said plate.

In testimony whereof I affix my signature. 55
WILLIAM D. BELL.
